(57) **CLAIM**

The ornamental design for a trash container, as shown and described.

DESCRIPTION

FIG. 1 is a top plan view of a trash container embodying my new design;

FIG. 2 is a front elevational view thereof;

FIG. 3 is a rear view thereof;

FIG. 4 is a side elevational view thereof, the side not shown being a mirror image of the side shown;

FIG. 5 is a perspective view thereof, the bottom thereof being plain;

FIG. 6 is a top plan view of a trash container embodying a modified form of my new design;

FIG. 7 is a front elevational view thereof;

FIG. 8 is a rear view thereof;

FIG. 9 is a side elevational view thereof, the side not shown being a mirror image of the side shown; and,

FIG. 10 is a front perspective view thereof, the bottom thereof being plain.
